(57) **CLAIM**

The ornamental design for an adjustable stand for concrete chute, as shown and described.

DESCRIPTION

FIG. 1 is a left front perspective view showing our new design.

FIG. 2 is a right front perspective view thereof.

FIG. 3 is a left-side view thereof.

FIG. 4 is a front view thereof.

FIG. 5 is a top view thereof.

FIG. 6 is a right-side view thereof.

FIG. 7 is a back view thereof.

FIG. 8 is a bottom view thereof.

FIG. 9 is a left front perspective view showing our new design in an alternate position.

FIG. 10 is a right front perspective view of FIG. 9.

FIG. 11 is a left-side view of FIG. 9.

FIG. 12 is a front view of FIG. 9.

FIG. 13 is a top view of FIG. 9.

FIG. 14 is a right-side view of FIG. 9.

FIG. 15 is a back view of FIG. 9; and,

FIG. 16 is a bottom view of FIG. 9.
